Joseph Michener of Chester Township Ohio
Inventor

The Schedule referred to in the Letters Patent and making part of
the same containing a description in the words of the said Joseph
Michener herewith of his Improvement in a machine for propelling
carriage for saw mills.

To all whom these presents shall come. Be it known that I
Joseph Michener of Chester Township and County of Clinton and
and State of Ohio have invented a new and useful improvement
in a machine for propelling carriage for saw mills and that the
following is a full and exact description of the construction and op-
eration of said machine as invented or improved by me.

C is the carriage. R the Rolling in which the carriage moves. W.
G. is the way and guide. A rope may pass round the shaft of
the rag wheel twice, which rag wheel and shaft is represented in
frame between G and W. which will supply the place of rag wheel.
